UNITED STATES PATENT OFFICE.

ELWOOD C. PHILLIPS, OF CHICAGO, ILLINOIS.

COIN-AND-SLOT MACHINE FOR TOOL-SHARPENING.

SPECIFICATION forming part of Letters Patent No. 443,001, dated December 16, 1890.

Application filed August 14, 1890. Serial No. 361,973. (No model.)

To all whom it may concern:

Be it known that I, ELWOOD C. PHILLIPS, a citizen of the United States, residing at Chicago, in the county of Cook and State of Illinois, have invented certain new and useful Improvements in Coin-and-Slot Machines for Tool-Sharpenering; and I do hereby declare the following to be a full, clear, and exact description of the invention, such as will enable others skilled in the art to which it appertains to make and use the same.

The object of this invention is to provide for the automatic presentation of a knife-sharpening stone in position for such use when a coin is dropped in the slot of the machine; also to provide for the automatic dislodgment of such coin as a result of the act of sharpening, and to insure the withdrawal of the stone from its sharpening position after a given amount of use and until another coin is deposited.

In the accompanying drawings, Figure 1 represents a perspective view of the casing of the machine embodying my invention. Fig. 2 represents a vertical transverse section taken through such machine on the line of the center of the stone. Fig. 3 represents a detail view, partly in side elevation, partly in section, of the ratchet-wheel, belt, and proportionate parts. Figs. 4 and 5 represent longitudinal vertical sections of said machine, taken on opposite sides of the ratchet-wheel; and Fig. 6 represents a horizontal longitudinal section of the same, taken in a plane above said wheel and belt.

A designates the casing which incloses the operative parts of the machine. In one end of the top of this there is a large opening A' for a knife-sharpening stone B, of emery or similar material, to protrude through when lifted. In the other and taller end of the top of said casing is a small slot a for the introduction of a cent or other small coin predetermined on. This coin falls through a zigzag passage C, the walls of which are attached to said casing on a small endless traveling belt D, which passes over and turns with small drums E F, mounted in a frame G, attached to one end of a lever H. This lever is pivoted at its middle on standards I, and bears at or near its other end a pivoted arm J, which is rigid with and supports a yoke or base K, re-

ceiving the said sharpening-stone B. The dropping of the coin on said belt causes the said lever to lift said sharpening-stone through opening A' in position for the knife to be used on it. To regulate this action exactly, the lever H is provided beyond said stone with a screw-threaded extension L, on which a screw-tapped weight M is adjustable backward and forward.

A pitman N extends back from the lower end of arm J, which is pivoted in the middle to an arm O, loosely mounted on the shaft E' of drum E and carrying a pawl O', which engages a ratchet-wheel P fast (as is also said drum) on said shaft. Through these connections the vibration of stone B during sharpening gives a step-by-step travel to said belt until the coin drops off. The stone continues to remain in position for sharpening by reason of a notched arm Q, which engages the frame G and prevents it from ascending. This arm is, however, provided with a finger R, which is struck and lifted at each complete rotation of said ratchet-wheel and its shaft by a cam S, fast on the latter. This disengages said notched arm or catch Q from said frame and the latter is free to ascend, the sharpening-stone descending correspondingly and simultaneously.

Pawl O' is provided with a spring o for holding it to its work, and a pivoted retaining-dog T prevents the backward motion of the ratchet-wheel. The sharpening-stone is protected by a glass cover U in a frame V, which is screwed to the top of said casing. Space is left between said frame and said stone for introducing the knife-blade and rubbing it on the latter.

Having thus described my invention, what I claim as new, and desire to secure by Letters Patent, is—

1. A lever bearing a knife-sharpening stone at one end and an attachment adapted to receive a coin at the other end, in combination with a casing having an opening for the protrusion of the stone and a slot for the dropping of the coin, substantially as set forth.

2. A coin-and-slot machine provided with a tool-sharpening device and intervening devices whereby the fall of the coin causes the sharpening device to be moved into position, for the purpose set forth.

3. In combination with a lever and a pivoted arm carried by one end thereof, a sharpening-stone supported by said arm, an endless traveling belt carried by the other end of
5 said lever, a ratchet-wheel on a shaft which operates the said belt, a pawl on a pivoted arm engaging said ratchet, and a pitman extending from the former arm to the latter, substantially as set forth.
- 10 4. A lever and a pivoted sharpener-supporting arm carried by one end thereof, in combination with an endless belt carried by the other end of said lever, a pitman, pawl, and

ratchet for causing the travel of said belt, a catch which prevents said belt from rising, 15 and a cam turning with said ratchet, which frees said catch at intervals and allows the belt to ascend and the sharpener to descend, substantially as set forth.

In testimony whereof I affix my signature in 20 presence of two witnesses.

ELWOOD C. PHILLIPS.
